UNITED STATES PATENT OFFICE.

JOHN F. MYERS, OF SAN FRANCISCO, CALIFORNIA.

DESIGN FOR A LAMP-STOVE.

SPECIFICATION forming part of Design No. 22,540, dated June 13, 1893.

Application filed November 28, 1892. Serial No. 453,426. Term of patent 7 years.

To all whom it may concern:

Be it known that I, JOHN F. MYERS, residing in the city and county of San Francisco, state of California, have invented and produced a new and original ornamental Design for Stoves, more especially to that class known as Oil or Gas Stoves, of which the following is a specification, reference being had to the accompanying drawings, forming a part thereof.

The leading features of my design consist of the head crown piece, of the side pieces, of the base, and of the band or rim having the shape, configuration or ornamentation shown.

Referring to the drawings—Figure 1, is a front elevation of the stove; and Fig. 2, a side elevation, showing fully shape of supporting band and base.

The open front A has three distinct parts. The crown piece C has a lower portion a and an upper portion a' in which are openings b , while its top b' is concavo-convex at b' and is ornamental at b'' . The lower portion is enclosed by longitudinal strips c . The side pieces C' are below the crown piece and have a marginal portion c^2 , an inner field c' and the inwardly projecting mantel or brack-

ets d . The base is concavo-convex and has the ornamental open front D and the ornamental ends D' . The rim, E, is in rear of the base and has its lower edge on a compound curve from e' and e'' and then carried downward merging into the edge of the leg E'. The portion f of the rim has openings f' which are arranged to form an ornamental design. The foot rest F' is curved outwardly and inwardly on compound lines and has downwardly projecting portions f'' .

Having thus described my design, what I claim as new, and desire to secure by Letters Patent, is—

1. The design for stoves substantially as shown and described.
2. In a design for stoves, the crown piece C substantially as described and shown. 45
3. In a design for stoves, the base D, substantially as described and shown.

In testimony whereof I have affixed my signature in the presence of two witnesses.

JOHN F. MYERS.

In presence of—

J. H. KEYS,
N. A. ACKER.
